COMBINATION HASSOCK AND
STORAGE BOX

Eileen Doern, New Rochelle, N. Y.

Application March 26, 1949, Serial No. 83,698

3 Claims. (Cl. 155—169)

1

This invention relates to hassocks, and more particularly to combination hassocks and storage boxes.

It is an object of my invention to provide an assembly for combination with boxes, such as hassocks, which will enable these devices to be used for storage of various articles, as well as by the introduction of this assembly and its attachment to the box to provide a more durable article of furniture, such as a hassock, thereby to increase the utility of such devices.

It is more specifically contemplated by my invention to provide in boxes such as made of fibreboard, combinations of plywood and fibreboard or any similar sheeting of relatively light weight and low cost customarily employed in making boxes and supplied with a readily removable lid, to include a partition assembly insertable in said box, to brace the lid and side walls effectively, rendering the box convertible into a hassock as well as to serve as a means for storage of articles such as may be employed in the home, workshop or showroom.

Still more specifically it is contemplated by my invention to provide a storage box having a readily removable lid and made from light weight sheeting material, such as wood-veneer reinforced paper, plywood, and which normally may not be sufficiently strong to withstand continued use while holding its form and shape and to sustain the weight of a human body seated thereon when formed into a box and to include a reinforcing assembly which optionally is readily saleable in a knocked-down condition for quick insertion into the box, thereby effectively bracing the lid while providing partition storage cells in the box.

To attain these objects and such further objects as may appear herein, or be hereinafter pointed out, I make reference to the accompanying drawings forming a part hereof, in which—

Figure 1 is a perspective view illustrating my device;

Figure 2 is a magnified plan view thereof with the lid removed;

Figure 3 is a section taken on the line 3—3 of Figure 2, with the lid replaced;

Figure 4 is a magnified section taken on the line 4—4 of Figure 3;

Figure 5 is a fragmentary section of a column in accordance with another embodiment of my invention.

Making reference to the drawing, the invention may be illustrated in conjunction with a cylindrical box 10 whose side wall 11 may be formed of a variety of relatively stiff sheeting, such as

2

wood-veneer reinforced paper, referred to in the trade under the name of "Tekwood," fibreboard, heavy cardboard, triple ply corrugated board, which may be bent along deep radii without breaking. I prefer to employ the Tekwood of $\frac{1}{8}$ " thickness or wood-veneer reinforced paper of that total thickness, which, upon being moistened, may be readily bent into cylindrical contour about a radius from 7 to 20". These dimensions are illustrative, as will be readily understood.

In the construction illustrated, the wall defining sheeting is formed with a bottom 12 which may be formed of plywood, to which the cylindrical wall 11 may be tacked or adhesively bonded at the perimeter 13. A lid 14 is formed as is the bottom 12, with an overlapping ring 15 affixed at the perimeter 16. This construction is completed by joining the edges 17 with another overlapping strip joining the co-terminous edges, or by attaching together in overlapping position the free ends thereof. The construction thus described, where made of the sheeting material described, and made in sofa size as I contemplate producing it, cannot be assured as adequate under hard use to continually sustain the weight of one or more adults seated on the lid and with this burden to keep its shape.

I have found that I may provide a quick knock-down bracing assembly which also serves in the dual capacity of partitioning and dividing the box into a plurality of storage spaces by a partitioning assembly comprising a central column 18 over the upper end 19 of which there are positioned radial braces 20 and 21, in superimposed position, rabbeted to present their level surfaces flush to one another, with a driven fastening means 22 common to the two and entering the column 18 and about which driven fastening means the braces 20 and 21 may be rotatably adjusted from an overlying position to that at right angles to each other.

The ends 23 of each of the radial braces rest in butt joint contact with the side braces 24. The length of the column 18 and the thickness of the radial braces 20 and 21 make up a height lacking but a fraction of the width of the wall 11 up to its rim 25. This slight recess is to allow for felt or cotton padding which may be applied to the braces 20 and 21 to make a snug contact with the lid 14 and allow for some resiliency when the lid is sat upon.

The radial braces are arranged to extend diagonally over the column 18, leaving the walls 26 exposed. Those walls are formed with longitu-

dinal slots 27 in which the edges 28 of the partitions 29 may be slid, to abut the edge 28 against the column and extend the free end 30 against the inner surface of the cylindrical wall 11. The slots or grooves may serve to make frictional contact for the ends 28 of the partition by aligning the grooves or slots 27 with tissue, or batting to effect the frictional attachment previously mentioned, or, if desired, for a permanent arrangement by gluing the ends 28 within the groove 27.

While I have described a column 18 which is square in cross section and which supports four diametrically located radial braces and is grooved on four of its walls to receive four partitioning sheets which also act as braces to the side wall of the box, I have shown in Figure 5 another embodiment in which the column 18a is triangular in shape. Radial braces 20a have their meeting ends 21a cut in an angle of 120°, cooperating with the adjacent ends of the braces to form an endwise brace having a level surface common to the three braces described. The walls 26a are formed with grooves 27a, to receive three radially positioned partition braces 29a. In all other respects the construction is similar to that in the embodiment first described. The triangular partition assembly is desirable where the storage units are to be increased in size or where boxes of smaller diameters make it more desirable to partition the space into three compartments.

By the construction provided, the radial braces and partitions sustain the side walls 11 to provide a strong, solidly braced construction, especially where the edges 30 are affixed as by nailing or gluing to the inner surface of the vertical wall 11. The partitions 29 divide the box into storage compartments, making a device of high utility for home, workshop and showroom.

The assembly on its exterior may have attached to it, by adhesive or tacking operations, upholstery fabric with padding or quilting material to ornament the box and to protect the outside surface. When the lid 14 is positioned to close the box, a firm, durable hassock or sofa is provided which will withstand considerable loads and wear in use as intended.

It will be understood that while I prefer cylindrical shaped box members for combination with the brace insert, rectangular boxes, where so shaped from the sheeting may be employed.

It will thus be observed that I have provided a construction in which light weight boxes made of relatively light weight sheeting may be converted into decorative articles of furniture having utility for storage purposes.

Having thus described my invention and illustrated its use, what I claim as new and desire to secure by Letters Patent is:

1. In a lidded hassock or like storage box of light weight sheeting having a bottom and open top, the combination therewith of a partition assembly snugly interfitted and retained therein, said assembly comprising a column member resting on the bottom and extending to the top, radial braces mounted on the top of said member with their outer ends extending to the box walls, side braces for supporting the outer ends of said first braces, said column member having longitudinal grooves along their entire length and slidably receiving partitions extending from the column to the walls interrelatedly support-

ing said column and walls, respectively, said radial braces being supported on the top of said column at radial points between said partition members whereby the radial braces and the edges 5 of the partitions sustain the side walls and the lid thereon and whereby the partitions may be positioned in supporting positions on the column with the braces in the position aforesaid.

2. In a lidded hassock or like storage box made 10 of light weight sheeting comprising paper and wood veneer bent into a cylindrical box having a bottom and open top and having a lid provided with an overlapping ring for said top, the combination therewith of a partition assembly snugly 15 fitted in said box and including an axial column member supported on the bottom thereof, radial braces mounted on the top of said member with their outer ends extending over the opposite end of the column to the box walls, said column having longitudinal grooves and partitioning members extending from said column to said walls, said longitudinal grooves being open at the top of the column and said radial braces being supported on the top of said column at radial points 20 between said partition members whereby the radial braces and the edges of the partitions sustain the side walls and the lid thereon and whereby the partitions may be positioned in supporting positions on the column with the braces in the position aforesaid.

3. In a lidded hassock or like storage box made 25 of light weight sheeting comprising paper and wood veneer laminations formed into a cylindrical box having a bottom and open top and including an overlapping lid for said top, the combination therewith of a partition assembly snugly fitted in said box and comprising an axial column member supported on the bottom, radial braces mounted on the top of said member with their outer ends overlying the upper end of the column with their outer ends extending adjacent the rim of said box, side braces supporting the outer ends of said first braces, said column having longitudinally extended grooves and partition sheets held in said grooves and extending 30 into wall bracing position, said grooves extending to the top of the column holding said partition members coterminously therewith and said radial braces being supported on the top of said column at radial points between said partition members whereby the radial braces and the edges 35 of the partitions sustain the side walls and the lid thereon and whereby the partitions may be positioned in supporting positions on the column with the braces in the position aforesaid.

EILEEN DOERN.
